UNITED STATES PATENT OFFICE.

JOHN W. T. GILLIAM, OF BALTIMORE, MARYLAND.

INSIDE WINDOW-BLIND.

SPECIFICATION forming part of Letters Patent No. 484,957, dated October 25, 1892.

Application filed April 30, 1892. Serial No. 431,305. (No model.)

To all whom it may concern:

Be it known that I, JOHN W. T. GILLIAM, a citizen of the United States, residing at Baltimore, in the State of Maryland, have invented 5 certain new and useful Improvements in Inside Window-Blinds, of which the following is a specification.

This invention relates to an improvement in inside window-blinds; and the object is to 10 provide flexible blinds to roll up and be contained in casings at the sides of the window when not in use and to draw out across the window in suitable guides.

To this end the invention consists in the 15 novel features of construction and combinations of parts hereinafter described.

In the accompanying drawings, which illustrate the invention, Figure 1 shows an elevation of a window from the inside with the 20 casing at one side in section and the two upper blinds drawn out and one of the lower blinds partly drawn out. Fig. 2 is a vertical section on line 2 2 of Fig. 1. Fig. 3 shows a horizontal cross-section of one side of the casing on line 3 3 of Fig. 1. Fig. 4 shows a top view of the middle journal block or box with lid removed to disclose the spring and shows the roller in section, and also the casing in 25 section.

30 The letter A designates the window-sill; B, the top front piece of the frame; C, the front pieces of the casing, and D the side pieces of the casing. The corners of the window-framing are boxed up by the molding-strips

35 E and the inside pieces F to form boxes or casings extending the height of the window. The inside pieces F leave openings or slots a between them and the front pieces C of the casings. Each of such casings has block G, 40 secured in it at the middle and turned out in the upper side to form a circular chamber b, while in the under side it has a socket c. A roller H journals at one end in a block I, secured to the top of the casing, and at the opposite or lower end in a lid J, secured over the box G. Said box contains a spring K, in the 45 present instance having the form of a clock-spring, which is fastened at one end to the roller and at the other to the box, and is contained in the chamber b. A similar roller L is journaled at its upper end in the socket c

of the block G and at its lower end in a box which consists of a turned-out block M, secured to the sill A, and containing a spring N, fastened to the roller and block. A flexible blind O, made up of wood strips connected by interposed canvas or other suitable material O', is fastened to each roller by passing one end of said canvas about the roller and suitably securing it thereto. Grooved guide-strips P are secured to the top and bottom of the window-frame, and at the middle of the said frame, at about the position of the meeting-rails of the sashes, a cross-bar Q is fastened to the front pieces C of the casing by 55 screws or other means and is grooved in its upper and lower sides and extends across the window.

The blinds slide in the grooves of the strips P and cross-bar Q and are guided thereby. 7c

A rack R is on the upper edge of the bar Q at each side of the window, and a pawl d is pivoted to each upper blind O and engages one of said racks. Likewise racks S are on the upper edge of the lower guide-strip P, and the two lower blinds each have a pivoted pawl e for engaging the same. Each blind has a knob f by which to draw it out. 75

Each blind is of such a length as when drawn out to come to the middle of the window, and it will be seen that upon drawing out a blind the spring on its roller will be wound up, whereby said spring will draw the blind back into the casing when released and wind it upon the roller. 80

The pivoted pawl on the blind dropping into the teeth of the rack on the guideway will hold the blind at any position it is desired to set it and serves as an automatic means for holding the blind wherever it is 90 stopped.

It will be observed that with my construction the blinds are wholly concealed within the casing and out of the way when not in use; but can be very readily brought into use by 95 simply drawing them out in their guideways by the knobs f.

Where two blinds meet at the middle of the window, they will each have a rabbet, so as to overlap and completely close the window. 100

Another advantage of my construction is that any desired portion of the window may

be shaded, as the blinds all work independently of each other, and any one of them may be set at any position desired.

If the upper blinds are so high up as to be 5 out of reach, a cord *g* will be attached to each and run over a pulley *h* at the side of the casing, and thence depend so as to be readily accessible. It will be seen that by pulling down on these cords the blinds will be drawn 10 out.

When the blinds are to be opened, the pawls are lifted out of engagement with the racks, which permits the blinds to be drawn back into the casings by their springs.

15 The usual appearance of the window-framing is not affected by the application thereto of my improved blinds, as I simply utilize the boxes of the casing or jamb for containing the wound-up blinds. There is ample room 20 left for hanging roller-shades and lace curtains, and it will be seen my style of blinds possess an advantage over others in that they do not in any way interfere with the curtains.

A window may be very easily fitted with 25 this style of blind. The rollers will be first fitted into their boxes or blocks and then introduced into the casings and the boxes.

or blocks secured in place and the casings closed up.

It is evident changes may be made in the 30 construction here shown and described without departing from my invention.

Having thus described my invention, what I claim as new, and desire to secure by Letters Patent, is—

35 The combination of a window frame or casing having horizontal slideways, one side of one of which constitutes a rack, a spring-roller mounted vertically in bearings at one side of the said window-frame, a flexible blind secured to and winding on said roller and fitting said horizontal slideways of the window-frame, and a pawl carried by the flexible blind and adapted to automatically engage the said rack, and thereby hold the blind at various 40 positions to which it may be drawn out against the action of the spring-roller.

45 In testimony whereof I affix my signature in the presence of two witnesses.

JOHN W. T. GILLIAM.
